UNITED STATES PATENT OFFICE.

JOHN H. DOWNING, OF MINNEAPOLIS, MINNESOTA, ASSIGNOR TO STATE OF MINNESOTA.

OPERATING MECHANISM FOR MANURE-SPREADERS.

1,178,995.

Specification of Letters Patent.

Patented Apr. 11, 1916.

Application filed July 26, 1915. Serial No. 41,906.

To all whom it may concern:

Be it known that I, JOHN H. DOWNING, a subject of the King of England, resident of Minneapolis, county of Hennepin, State of Minnesota, have invented certain new and useful Improvements in Operating Mechanism for Manure-Spreaders, of which the following is a specification.

My invention relates to that class of devices designed for regulating the travel of an apron or belt in the bottom of a wagon box for the purpose of accelerating or retarding the feed of the material from the box.

15 The object of my present invention is to provide a simple, inexpensive construction by means of which the speed of the feed apron can be increased or stopped entirely at the will of the operator of the machine.

20 The invention consists generally in various constructions and combinations, all as hereinafter described and particularly pointed out in the claims.

In the accompanying drawings forming 25 part of this specification, Figure 1 is a plan view of a portion of the rear end of a manure spreader with my invention applied thereto, Fig. 2 is a longitudinal sectional view, illustrating the apron controlling 30 mechanism.

In the drawing, 2 represents a wagon box, 3 an axle, and 4 carrying wheels.

5 5 is an apron or belt, operating in the bottom of the wagon box, as usual in machines of this type, and driven from a shaft 6. On this shaft is a ratchet wheel 7, the teeth of which are engaged by dogs 8 mounted in a frame 9. This frame is journaled on the axle 6 and has an oscillating 40 movement thereon to feed the ratchet wheel 7 and the apron. A guide 10 is mounted on the wagon box, in which a bolt 11, carried by the frame 9, is slidable. A lever 12 is pivoted at one end on the bolt 11 and provided with a longitudinal slot 13. An arm 14 is pivoted at one end on the wagon box and has a pin 15 passing through the slot 13 and slidable therein and forming a fulcrum for the lever 12. An operating rod 16 45 extends from the upper end of the arm 14 to a lever at the forward portion of the machine, not shown. By means of this lever and the rod 16, the driver can move the arm 14 back and forth on its pivot, change the 50 position of the fulcrum 15 in the slot 13 and

regulate the degree of oscillation of the lever 12 according to the desired feed of the apron. When this fulcrum is moved to the extreme rear end of the slot 13, the oscillation of the lever will be so slight that the movement of the dogs will not be sufficient 60 to operate the ratchet wheel and the feed apron.

In the position shown in Fig. 2, the fulcrum is at the extreme forward end of the slot and the lever will in this position have its greatest range of oscillation, and the travel of the feed apron will be correspondingly increased.

A gear 17 is mounted on the axle 3 and a 70 belt 18 connects this gear with a pinion 19 on a shaft 20. A crank arm 21 is mounted on this shaft and a link 22 pivotally connects this crank arm with the forward end of the lever 12 and through this connection the 75 lever is oscillated to operate the feed dogs and move the feed apron. A guide bar 23 is mounted on the box 2 to prevent lateral movement of the lever 12 during its vertical oscillation. It is only necessary, therefore, 80 for the driver of the machine to change the position of the arm 14 and easily and quickly rock the lever and vary the feed of the apron or stop it entirely.

Near the rear end of the apron I mount 85 a beater 24 of ordinary construction, having teeth 25 in the path of the material discharged by the apron.

I do not wish to be confined to the form of ratchet mechanism herein shown, as it is 90 susceptible of considerable variation and still perform substantially the same functions and produce substantially the same result as far as the operation of the apron is concerned, the essential feature of my invention being the means for mounting the lever and shifting its fulcrum forward and 95 backward to regulate the degree of oscillation.

I claim as my invention:

1. In a manure spreader, a shaft for 100 transmitting motion to a manure carrier, a ratchet wheel connected with said shaft, a pivoted frame having dogs engaging the teeth of said wheel on opposite sides of the 105 axis thereof, a rocking arm, a slotted lever pivotally connected with said frame and having a fulcrum on said arm, said arm being free to rock forward and backward in said slot for shifting the fulcrum of said 110

lever to vary the stroke of said frame, and the movement of said ratchet dogs, and mechanism for rocking said lever.

2. In a manure spreader, the combination with a shaft for transmitting motion to a manure carrier, of a ratchet wheel connected therewith, dogs mounted to engage the teeth of said ratchet wheel on opposite sides of the center thereof, an arm mounted to 10 rock in a vertical plane, a fulcrum pin carried by said arm, a lever connected with said ratchet dogs and having a longitudinal slot to receive said fulcrum pin, said lever being held against longitudinal movement but free 15 to rock in a vertical plane on its fulcrum, and means for moving said arm forward and backward to shift the fulcrum of said lever and vary the travel of said ratchet dogs, and mechanism for operating said lever in 20 a vertical plane.

3. In a manure spreader, the combination with a shaft for transmitting motion to a manure carrier, of a ratchet feed mechanism comprising a wheel, and ratchet dogs therefor, a lever pivotally connected with said dogs and having a longitudinal slot therein, a rocking arm having a fulcrum for said lever in said slot and movable back and forth therein to vary the position of the

fulcrum of said lever and the stroke of said dogs, means for rocking said lever, and shifting means for said arm.

4. A ratchet feed mechanism comprising a ratchet wheel and transmission shaft, a frame and ratchet dogs mounted thereon to 35 engage the ratchet wheel, a lever having a pivotal connection at one end with said frame and provided with a longitudinal slot adjacent to said pivotal connection, an upright arm pivoted at a point adjacent to 40 the axis of said wheel to rock in a plane parallel with the plane of said wheel and provided with a fulcrum pin that is mounted to slide in said longitudinal slot, an operating rod connected to the upper end 45 of said arm for shifting it forward or backward to change the fulcrum of said lever, a crank arm, and a link pivotally connecting said arm with said lever at the end opposite its pivotal connection with said frame.

In witness whereof, I have hereunto set my hand this 20th day of July, 1915.

JOHN H. DOWNING.
